EDWARD A. OWENS, OF SAN FRANCISCO, CALIFORNIA, ASSIGNOR TO SELECTASINE SYSTEM INC., OF SAN FRANCISCO, CALIFORNIA, A CORPORATION OF CALIFORNIA.

METHOD OF MAKING MULTICOLOR PICTURES.

Application filed April 14, 1920. Serial No. 373,828.

To all whom it may concern:

Be it known that I, EDWARD A. OWENS, a citizen of the United States, residing at the city and county of San Francisco and State of California, have invented a new and useful Improvement in Methods of Making Multicolor Pictures, of which the following is a specification.

This invention relates to a method of delineating or reproducing pictures and designs and is in a general way similar to the method of delineating or reproducing pictures and designs described in a co-pending application filed April 16, 1919, entitled, "Method of delineating or reproducing pictures, etc." Serial No. 290,374. It is in the nature of a modification or outgrowth of Patent No. 1,254,764, dated January 29, 1918.

20 The purpose of the co-pending application referred to was to provide a method of reproducing a multi-color picture through the use of opaque colors and screens, whereby the different color areas deposited or run 25 through a screen are permitted to join each other along marginal lines and when so applied form a single coat or layer of adjoining colors. In other words, in this co-pending case and in the present instance 30 there is no superimposing of colors and plateau building, producing an embossed effect as in Patent No. 1,254,764, above referred to. While the method of the co-pending application for producing colored pictures results 35 in a product of great beauty and novelty and is quite suitable under some conditions, it however lacks the clear cut features and definite outlining which is sometimes required.

40 The purpose of the present invention is to overcome this objection by providing a method whereby the colored areas may be outlined by definite demarcations or "key lines" wherever desired, thus making it 45 possible to reproduce a picture or design which is difficult to distinguish from pictures produced by multi-color printing.

Another object of the invention is to provide a method whereby a picture or design 50 containing several colors may be clearly outlined and reproduced without overlaying of colors, on a semi-smooth or rough surface such as paper, leather, glass, metal, etc., by forcing the different colors through screens 55 and each color through a different portion

of a screen; further to provide a method whereby portions of a screen employed are first temporarily and then permanently masked as successive colors are transferred or applied. 60

The method will hereinafter be more fully described and claimed having reference to the accompanying drawings in which—

Fig. 1 is a view of the original multi-colored sketch or master pattern to be reproduced. 65

Fig. 2 is a view of the screen, showing the master pattern traced, photographed or otherwise reproduced thereon.

Fig. 3 is a view of the card before any 70 color is applied.

Fig. 4 is a similar view showing a blue color applied.

Fig. 5 shows the green color applied.

Fig. 6 shows a brown color. 75

Fig. 7 shows the last color, which is yellow, applied, and the reproducing operation completed.

Fig. 8 is a perspective of the stencil or screen frame through which the colors are 80 applied.

In conducting the present method of transferring colors when reproducing multi-color pictures or designs, a screen or tightly stretched bolting cloth, or other suitable material, is employed. This material is tightly stretched on a rigid wood or metal frame 3. The frame supporting the screen is placed over the drawing or picture to be reproduced and the outline of the picture is then traced 85 directly upon the screen. The picture may of course be otherwise transferred to the screen, for instance by photography or otherwise. The picture to be transferred is as stated traced upon the screen either by 90 pencil or ink. This tracing is an outline of the picture and will hereinafter be referred to as the key line drawing. These "key lines" partially or wholly separate the several color areas of the picture; these "key lines" being 95 drawn in and then permanently masked or blocked out so that no paint can be forced through these lined portions, nor will the lines nor the masking material applied over them be erased or removed during subsequent operations. 100

There are several masking materials that may be employed, among which may be mentioned, glue, varnish, shellac, etc. These masking materials are soluble in different 110

degrees and in different substances; some being soluble in one thing and not in another. Thus glue is soluble in water; varnish in turpentine, and not in water; and 5 shellac in alcohol, but not in water or turpentine. Of course other masking materials may be employed, for instance, such as stencils cut from paper, tissue, metal, or any other material best suited for the work in 10 hand.

For the purpose of clearly explaining the masking out method, we will assume that shellac is employed for the purpose of permanently masking out the "key lines" of the 15 picture and any color area which it is desired to permanently retain. The shellac, where a fluid-like mask is used, is applied by a pen or a brush and the outlines of the picture are therefore traced with shellac. Manifestly these "key lines" may be fine hair 20 lines or may be heavier according to the effect desired. This first blocking or masking step of the process which embodies the "key lines" and color areas to be permanently retained, such for example as the 25 surface color of the card e. g. black, is what is known as a permanent blocking out step, since these "key lines" and the restricted areas of the foundation color of the card, 30 e. g. black, on the screen will not be re-opened, i. e. made permeable to paint at any time during the reproduction of the picture and in fact are never re-opened or removed unless it may be desired to employ the screen 35 for other pictures.

In making picture reproductions, such as here shown, on non-transparent materials, such as paper, leather, metal, etc., it is desirable to save as much coloring matter as 40 possible. The color of the card employed is therefore selected as a base color, for example in this instance, black, as shown in Fig. 3. All black areas or "key lines" that it is desired to retain, are therefore permanently 45 masked out, thereby rendering it unnecessary to run a black color, thus saving coloring material to this extent, and also saving the labor and time involved, due to the fact that one color run will be eliminated. It 50 may however happen that a base coloring of desired effect is not obtainable and that the "key line" and other color areas may have to be applied. This can be accomplished by first masking out the "key lines" and the 55 color areas referred to and then applying the several other color areas, then masking out said color areas and opening up the "key lines" and the first color areas referred to and finally applying the "key lines" and 60 color areas by transferring any color desired. In other words the "key lining" of the picture would be the last step of the process. This step of the process is however only resorted to when the base color of 65 the material used is not suitable and its use

is otherwise only resorted to when printing on glass where it is desired to obtain a transparent "key line" picture.

After the permanent masking of the "key lines" and other limited areas has been accomplished, the next step is blocking or masking with a temporary mask, such as glue, all the color areas or portions of the screen except that through which the first color is to be run.

By referring to the different views of the drawings it is assumed that it is desired to apply blue as the first color. Hence all of the color areas on the screen are masked or blocked out temporarily with the exception 70 of the blue areas which comprise the sky and windows so that when the blue color is deposited upon the screen no portion of the card under the screen will receive paint or color except that portion where it is desired to apply the blue.

Any suitable temporary masking material may be employed, as for instance glue. This glue is applied to all portions of the screen except where the blue color is to be deposited and the meshes of the screen are therefore merely temporarily closed by filling the interstices of the screen. This masking prevents any paint from passing through and as the main area or picture of the screen 80 is blocked with glue, which is soluble in water, it is obvious that any desired portion thereof may be re-opened whenever it is desired to apply another color by simply washing out the glue covering that particular 85 portion, but without disturbing any of the rest of the screen.

The face of the card upon which the colors are to be deposited, that is which the picture is to be reproduced, is in this instance black as shown in Fig. 3 and all "key lines" and areas which it is desired to retain will therefore appear in black when the picture is completed. The outlines of the design are, as previously stated, traced or 105 painted out in skeleton form on the screen as shown in Fig. 2 by a stopping out or masking material, as for example, shellac, as this is not affected by the water when re-opening temporarily covered areas of the 110 screen. These outlines may be as heavily reinforced as desired if substantial "key lines" are required between colors or may be merely traced with ink and painted up to with the temporary masking material if each 115 color is to key or join the other, that is where definite "key lines" are not required. It is also possible by not quite blocking up to the traced outlines to insure that one color will slightly lap or margin on the other. This is 120 highly desirable in some instances and may be resorted to whenever required.

If black, the foundation color of the card is to form other parts of the picture, as for instance as here shown, the trees, the smoke,

the word House, and the margin line around the picture, it is retained by the first permanent masking operation which consisted in applying shellac to the "key lines" of the picture and to the color areas which it was desired to retain.

When a color is to be applied it is only necessary to place the card shown at 4 (see Fig. 3) below the screen stencil frame in such a manner that a perfect register is always obtained. The frame supporting the stencil screen, having the picture outlines thereon, is preferably hinged to a flat surface adapted to receive the cards from which the picture is to be reproduced, and any suitable means may be provided for securing a perfect register between the cards and the frame for each successive color run.

The colors employed are of suitable opaque plastic consistency and usually consist of water or oil color. In practice they are applied by pouring onto the screen surface and forcing the color through the open meshes by means of a flexible scraper, commonly known as a squeegee, operated by even pressure over the surface of the screen. The color applied is thus forced evenly through the open meshes of the screen and will adhere to the surface of the card and cover the parts desired. After each color is applied, the card is carefully set aside to dry before the next color is run.

Assuming blue, indicated at 5, (see Fig. 4) has been applied to all the cards, it is next necessary to change the screen to permit the application of the next color, in this case, green as shown at 6. (See Fig. 5.) This is accomplished by first thoroughly washing the screen with turpentine to remove all traces of paint. The turpentine neither affects the key line and permanent masking, nor the temporary masking since neither shellac nor glue are soluble in turpentine. Then that portion of the screen through which the blue color was run is permanently masked with shellac. Next that portion of the screen through which it is desired to transfer the green color is opened. This is accomplished preferably in practice by washing the entire screen with water until the glue or temporary mask has been thoroughly dissolved leaving unaffected the shellacked portion of the screen. Next it is again necessary temporarily to remask the open portions of the screen, except that through which the next color e. g. green is to be transferred. The screen is now ready for use and the green color will be applied by placing each successive card under the screen and forcing the green color through the same by means of the squeegee. Each card receives its green coat and is allowed to dry and the operation is continued until all the cards have been run for green.

65 The screen will then again be washed

with turpentine to remove all paint adhering thereto. Next, the portions of the screen which were open when the green color was applied will now be permanently masked out with shellac. Next, the portions which 70 represents the brown color, which it is assumed is the third to be run, and which still remain masked with the temporary mask. will be opened by washing out the glue with water, and reblocking for all except the 75 green areas. The brown color is then applied to each card. The screen is again washed to remove the paint and the cycle of operations repeated for each succeeding color until the final result produced is that 80 shown in Fig. 7.

From the foregoing it is seen that the screen stencil when first employed is entirely open; that the first step is that of tracing the "key lines" of the picture and the 85 color areas which it is desired to retain on the screen; that these "key lines" and color areas are permanently masked out with shellac or other suitable permanent masking agent; that the remaining area of the screen, 90 except that through which the first color is to be applied, is temporarily masked by means of glue or equivalent; that that area which remained opened during the first color run is permanently masked and that 95 the next area through which the color is to be run is open by removal of the temporary mask, either for the particular color area or for the entire screen and the screen remasked to leave uncovered only that portion through which the particular color is to be run; that each area after its particular color run is permanently masked so that the entire screen finally becomes permanently masked out with the exception of that portion through which the last color is run.

It will further be seen that the respective colors are run through different portions of the screen and that no two colors are forced through the same portions or 100 meshes of the screen. In other words the colors are applied in single layers side by side and not superimposed as in the patented process aforesaid. The present method is of great practical importance as it permits the economical reproduction of multi-colored pictures closely resembling those made by the more expensive methods of lithography and printing.

By this method of blocking out the 120 screen and running the colors, pictures with clean cut margins are reproduced and with even greater brilliance than is attained by lithographing or three-color printing.

The invention is also useful for printing 125 transparent material where light shining through the same would otherwise show joints of overlapping colors or produce a ragged and undesirable effect.

In making glass signs all the colors of 130

the design are first run and the "key lines" and back ground color are applied last. Glass signs are printed on the back usually and in this case the marginal lines between 5 the color patches would be open and would allow the glass to show through until the black was run. This color may be applied by two different methods and would give the design its definition or outline. One 10 method of applying the key lines is to mask out the entire screen, for instance with glue and then open the key lines of the picture, which have been blocked out with shellac, by washing the screen with alcohol. The 15 black color applied would therefore pass through the key lines and would fill the space between the different color areas and thereby give the outline or definition desired. Again after the several colors have 20 been run, it would be possible to give the picture its definition by applying a coat of black paint to the entire surface. This picture would however not be transparent due to the black backing coat applied.

25 While the description specifies a screen supported or otherwise tightly stretched on a rigid frame, it is understood that the screen proper may be stiffened to such an extent that a frame may not be required, 30 and it is also possible that it may be otherwise supported; similarly while a single screen is in most instances employed to advantage, it is understood that two or more screens may be employed if desired. In 35 other words the success of the present method is not dependent primarily upon the use of a single screen, although that is the preferred method in actual practice.

The discovery that different substances, 40 i. e. glue, shellac, etc., used in this process are soluble in different solutions, i. e. water, alcohol, etc., forms the subject matter of a separate application about to be filed by another.

45 Having thus described my invention, what I claim and desire to secure by Letters Patent is—

1. A method of producing multi-color pictures which consists in running successive colors through a screen, each color 50 through a different portion of a screen, and each color area separated by key lines upon the screen.

2. A method of producing multi-color pictures which consists in running successive colors through a screen, each color 55 through a different portion of a screen and certain color areas run defined and separated by key lines.

60 3. A method of reproducing multi-color pictures or designs which consists in forcing a succession of colors through a screen and each color through a different portion of a screen and in such a manner that adjoining color areas are separated.

4. A method of reproducing multi-color pictures or designs which consists in tracing a skeleton outline of the picture to be reproduced upon a tightly stretched screen, 70 said outline enclosing the different color areas of the picture, permanently masking said outline, temporarily masking all areas except where a color is to be transferred through the screen, opening the next color area to be run and permanently blocking 75 each area after a color has been run therethrough.

5. A method of masking stencil screens when reproducing color pictures, designs, etc., which consists in transferring the key 80 lines of the picture to a screen, applying a permanent masking-out material on said key lines, covering the remaining area of the screen with a temporary mask, except where the first color is to be transferred 85 through the screen, permanently masking out said area after the color transfer, removing the temporary mask where the next color transfer takes place, and permanently remasking each area after a color transfer 90 until the entire screen is permanently masked, except that portion through which the last color is to be transferred.

6. A method of masking stencil screen when reproducing colored pictures, designs, etc., which consists in transferring the key 95 lines of the picture to be reproduced to the screen, applying a masking material to said key lines, applying another masking material on the remaining areas of the screen, 100 except where the first color is to be transferred through the screen, permanently masking said areas after the color transfer, removing the last named mask where the next color transfer takes place, permanently 105 masking each area after a color has been transferred therethrough, and finally removing the keyline mask to transfer a key line color therethrough.

7. A method of reproducing multi-colored 110 pictures or designs which consists in running successive colors through separate stencils adapted to be supported by gauze-like material, each color area being separated by key-lines forming a part of each 115 stencil and each color area defined and separated by said lines.

8. A method of reproducing multi-colored pictures or designs which consists in forcing a plurality of colors through a plurality of stencils through the medium of a screen supporting the stencils, each color being forced through a different area of the screen and the detail defined by key-lines forming a part of each stencil. 120

9. The method of producing multicolored pictures by means of a screen which consists of forming an outline of the picture on the screen, blocking out all other portions of the screen except those portions through 130

which a single color is to be forced, in then forcing coloring material through the un-blocked portions of the screen upon the article to be colored, then reblocking said screen to block out all portions thereof except those portions through which another color is to be forced and constituting a portion of said screen through which color was not forced in the first stenciling step, and in forcing another coloring material through the portions of the screen left open on the reblocking operation, upon a different portion of the article to be colored than that to which the first coloring material was applied.

10. The method of producing multicolored pictures by means of a screen which consists of forming an outline of the picture on the screen with a material which will remain permanent during the several blocking and stenciling operations, blocking out all other portions of the screen except those

portions through which a single color is to be forced, in then forcing coloring material through the un-blocked portions of the screen upon the article to be colored, then reblocking said screen to block out all portions thereof except those portions through which another color is to be forced and constituting a portion of said screen through which color was not forced in the first stenciling step, and in forcing another coloring material through the portions of the screen left open on the reblocking operation, upon a different portion of the article to be colored than that to which the first coloring material was applied.

In testimony whereof I have hereunto set my hand in the presence of two subscribing witnesses.

EDWARD A. OWENS.
